ROBERT BERRIER KETTLEWELL, OF HARROGATE, ENGLAND, ASSIGNOR TO YOST WRITING MACHINE COMPANY, OF ILION, NEW YORK, A CORPORATION OF NEW YORK.

TYPE-WRITING MACHINE.

1,092,841.

Specification of Letters Patent.

Patented Apr. 14, 1914.

Application filed December 30, 1912. Serial No. 739,292.

To all whom it may concern:

Be it known that I, ROBERT BERRIER KETTLEWELL, a subject of the King of Great Britain and Ireland, and resident of Harrogate, county of York, England, have invented new and useful Improvements in Type-Writing Machines, of which the following is a specification.

My invention relates to typewriting machines and more particularly to tabulating mechanism.

One of the main objects of my invention is to provide comparatively simple and efficient column selecting means whereby any one of 15 a relatively large number of columns may be readily selected by actuating a corresponding column selecting key.

A further object of the invention is to so combine such column selecting mechanism 20 with denominational selecting means that any desired denominational position may be obtained in any selected columnar field.

Another object of my invention is to provide a construction in which the same column stop with which the column selecting mechanism co-acts to select a column may afterward be engaged by a denominational stop to select a denominational position within the selected columnar field.

30 A still further object of my invention is to provide means of the character specified which may be readily embodied in existing typewriting machines such as the No. 20 Yost machine, for example, without modifying, or materially modifying, the structural features of said machines as they now exist.

To the above and other ends which will hereinafter appear, my invention consists in the features of construction, arrangements 40 of parts and combinations of devices to be hereinafter set forth and particularly pointed out in the appended claims.

In the accompanying drawings wherein like reference characters designate corresponding parts in the different views, Figure 45 1 is a fragmentary central fore and aft vertical sectional view of one form of typewriting machine embodying my invention. Fig. 2 is a diagrammatic plan view showing the 50 arrangement of the indicator and the column selecting keys. Fig. 3 is a fragmentary plan view of the column stops, the column selecting stops and the denominational stops, together with some of the associated parts. 55 Fig. 4 is a fragmentary front elevation with

parts in section of the column selecting stop carrying members and the levers by which they are actuated.

I have shown my invention embodied in the present instance in a No. 20 Yost machine in which the invention may be readily included without modifying, or materially modifying, the structural features of said machine as they now exist. It should be understood, however, that the invention may 60 be embodied in the nature of an attachment in various styles of typewriting machines.

As shown in the accompanying drawings, the frame of the machine comprises side plates 1, a rear cross plate 2, a front cross plate 3 and top plates 4 and 5. The side plates support fixed oppositely grooved guide rails 6 which receive anti-friction rollers 7, the latter being likewise received in oppositely grooved guide rails 8 of a carriage truck 9. A platen frame 10 is supported on the truck in the usual manner and carries a rotative platen 11. The carriage is connected in the ordinary manner with a spring drum (not shown) for movement under the power of the drum from right to left over the top plates of the machine. Depending arms 12 are pivoted at 13 to the truck and carry a feed rack 14 which meshes with a feed pinion 15. This feed pinion is 80 carried by a shaft which extends through a fixed retarder drum 16 and has a sleeve 17 surrounding the shaft near the lower end portion thereof. This sleeve is connected to the shaft by means of a spline 18 which causes the sleeve to rotate with the shaft but 85 enables the sleeve to receive a vertical movement on the shaft. A pawl 19 is carried by a yoke-like member 20 which is pivoted on the sleeve 17. The pawl is adapted to engage teeth 21 on the hub of an escapement wheel 22 which surrounds the shaft at the lower end portion thereof. When the sleeve 17 is in the lowermost or normal position the pawl 19 engages the teeth 21, thus effecting 90 an operative connection between the escapement wheel and shaft to cause the two to rotate together. A second sleeve 23 is slotted at 24 to receive a pin 25 which is connected with a collar 25^a of a rotative retarder member contained within the fixed drum 16. The lower end of the sleeve 23 is 95 provided with clutch teeth 26 which are cooperative with corresponding teeth 27 formed in the upper end of the sleeve 17. 100

105

110

It will be understood that an upward movement of the sleeve 17 is effective to disengage the pawl 19 from the escapement wheel and to bring the teeth 27 into clutching engagement with the teeth 26 so as to operatively connect the escapement wheel shaft with the retarder. This movement of the sleeve 17 is effected by releasing means which are constructed as follows: The sleeve 17 has circumferential flanges 28 forming a circumferential groove between them and in which inwardly projecting pins 29 on a release lever 30 are received. This release lever is bifurcated at its forward end to form a yoke-like portion where it carries the pins 29, the lever being pivoted at 31 to a depending post 32 supported by a fixed portion of the machine. This lever is actuated in a manner which will hereinafter appear.

Upwardly and rearwardly extending bracket arms 33 project from the carriage truck and support a column stop bar 34 which upon reference to Fig. 1 will be seen to be substantially H-shaped in cross section. The upper and lower sides of this column stop bar are grooved as at 34^a to receive bifurcated column stops each designated as a whole by the reference numeral 35. The column stops in the present instance are shown to be sixteen in number and may be adjusted to different positions along the stop bar 34. Each of these column stops is provided with what I term a denominational selecting engaging portion 36. The various engaging portions 36 on the different column stops are arranged in a single line transversely of the machine so that they all move in a single path.

A guide comb or plate 37 is fixed to the top plate 4 and receives upwardly extending arms 38 which form parts of denominational stop levers. These levers are pivoted at 39 to a fixed portion of the machine and have forwardly extending arms 40 which are engaged by key stems 41. These key stems are guided in guide openings in plates 42 and 43 fixed to the frame of the machine. The upper end of each denominational stop lever projects through a slot 50 in the guide comb or plate 37, the projecting portion of each lever forming a denominational stop 44. Each denominational stop lever is connected to one end of a contractile spring 45 which has its opposite end connected to a fixed plate 46 secured to the base of the machine. A universal release bar or plate 47 is pivotally mounted at 39 on the same pivot on which the denominational stop levers are mounted. This release plate 47 extends beneath the various denominational stop levers and is adapted to be turned thereby during the depression of a denominational key 48. An upwardly and rearwardly projecting arm 49 which is connected with the universal bar 47 is con-

nected to one end of a contractile spring 50, the opposite end of which is connected to the plate 46. The arm 49 is likewise connected to an upwardly extending link 51 which in turn is connected by means of a pin 52 and slot 53 to the release lever 30. It will be understood therefore that a depression of the denominational key is effective to move the associated denominational stop 44 into the path of the projections 36 on the column stop 35. This same depression of the key is effective to turn the universal bar 47, thereby effecting an upward movement of the forward end of the release lever 30 to release the pawl 19 from the teeth 21 and throw the clutch teeth 27 into engagement with the teeth 26. This releases the carriage from control of the escapement wheel and throws the carriage retarder into operation. So far as the denominational mechanism and the carriage releasing means above described are concerned they are somewhat similar to the corresponding mechanisms employed in the No. 20 Yost machine, except that different forms of column stops are employed in that machine.

I prefer to employ in conjunction with denominational stop mechanism such as that shown the column selecting mechanism of my present invention, so that any desired columnar field may first be selected and the denominational position within that field may be obtained by the denominational selecting mechanism. For this purpose each of the column stops 35 is also formed with what I term a column selecting engaging portion or projection 54 which extends rearwardly from the body portion of the column stop and has a distinctive path of movement with the carriage. There are, in the present instance, sixteen of these projections one on each column stop and each projection has a distinctive path of movement as will be understood from an inspection of Fig. 1. Co-operative with the engaging portions 54 are a series of column selecting stops 55, each of which also has a distinctive path of movement into and out of co-operative relation with the projection 54 on the particular column stop with which it co-acts. These column selecting stops 55 are formed as forwardly extending projections on a series of nested yoke-like substantially V-shaped stop carrying members 56. These members extend upwardly in the rear of the machine from a pivot rod 57 which is supported from the base of the machine by brackets 58 and each column selecting stop 55 is located at the apex of its V-shaped stop carrying member. From an inspection of the drawings it will be understood that the column selecting stops, although arranged at different heights to correspond to the arrangement of the engaging pro-

70

130

jection 54 on the column stops nevertheless have their contact faces all arranged in a single vertical plane which extends fore and aft of the machine. Moreover it will be understood from an inspection of Fig. 3 that the column selecting stops 55 are arranged to the right of the denominational stops 44 at a distance of, say, three letter spaces. It will be seen therefore that these column selecting stops in the movement of the carriage from right to left, are adapted to co-act with their respective column stops before the latter are brought into co-operative relation with the denominational stops.

It will be understood that the widely separated bearing points for the stop carrying members 56 on the pivot rod 57 offer an effective resistance to the impact of the carriage when it is arrested through the co-operation of any of the stops 54 with its co-operative column selecting stop 55. A series of levers 59 are pivoted on the rod 57 and extend forwardly beneath the machine where they connect with key stems 60, each provided with a column selecting key 61. These key stems like the key stems 41 are guided in openings in the guide plate 42 and in a second guide plate 62. There is a lever 59 provided for each of the yoke-like stop carrying members 56 and each lever 59 has an abutment 63 which co-operates with a corresponding abutment 64 on one arm of the associated stop carrying member 56 to form a butt or rule joint. A contractile spring 65 connects one arm of each stop carrying member 56 with its associated lever 59. This spring exerts a force to normally maintain the abutments 63 and 64 in contact so that each lever 59 and its associated stop carrying member 56 normally move together as one part. A stop or abutment 66 is fixed to the top plate 4 of the machine and extends into the path of the stop carrying members 56 near the upper end portions thereof. The construction therefore is such that on the depression of a column selecting key 61 the associated stop carrying member will be moved forwardly until arrested by the abutment or stop 66 when the stop carrying member is arrested; but a further movement of the lever 59 may be effected by reason of the spring 65 which connects said lever with the associated stop carrying member in order to effect a release of the carriage as will hereinafter appear. A forward movement of the stop carrying member thus effected brings the associated column selecting stop 55 into the path of a projection 54 on a given one of the column stops, and with no others since each projection 54 has a distinctive path of movement. It will be understood therefore that a column selecting stop 55 is co-operative with but one of the projections 54 on the column stops and that the carriage will continue to travel, when

released, until that particular projection 54 is brought into engagement with the interposed column selecting stop.

In order to effect a release of the carriage when a column selecting key is depressed I have provided a universal bar 67 which extends beneath the forward end portions of the levers 59 and is adapted to be actuated thereby. This universal bar is connected at its ends to levers 68 which are pivoted at 69 to depending bracket arms 70 carried by the frame of the machine. An arm 71 is connected to the levers 68 and this arm 71 is pivotally connected to an upwardly extending link 72 which in turn is connected at its upper end by a pin 73 and slot 74 to the release lever 30. It will be understood therefore that a depression of any of the column selecting keys is effective to depress the universal bar, thereby elevating the link 72 to effect an upward movement of the forward end of the release lever to release the carriage from control of the escapement wheel and throw the retarder into operation. At this time the pin 52 will move upwardly in the slot 53 of the releasing means connected with and controlled by the universal bar 47 of the denominational stop mechanism. In a like manner an actuation of the denominational stop mechanism will effect an upward movement of the pin 73 in the slot 74 so that the carriage release mechanism may be actuated by either the denominational stop mechanism or by the column selecting mechanism without interference from the releasing devices of the other mechanism.

The universal bar 67 is returned to normal position by springs 75 each of which is connected at one end to a lever 68 and at its opposite end to the plate 43. The universal bar 67 is limited in its upward movement by one or more stops 76, whereas the downward movement of the universal bar is limited by a stop 77, the stops 76 and 77 being carried by or formed from the plate 62.

Suitable means such as a sleeve 78 and washer 79 may be employed to maintain the stop carrying members 56 properly spaced apart on the pivot rod 57 and to hold them against movement along the rod.

From an inspection of Fig. 2 it will be seen that an indicator designated as a whole by the reference numeral 80 is arranged in the rear of the column selecting keys 61 and may be detachably supported in place by any suitable means. This indicator is preferably divided as shown so as to provide two rows of staggered elongated panels 81 each of which may be inscribed with suitable indices 82 which are aligned fore and aft of the machine with one of the column selecting keys 61. Any suitable indices to indicate the respective columns or the character of items to be written within the columns may be inscribed on the panels in

a staggered arrangement such as that shown. It will be seen therefore that while there is but a single row of tabulator keys 61 the indices for these keys are arranged in two rows, the indices in one row being staggered relatively to the indices in the other row and the indices for each key being alined therewith fore and aft of the machine. This arrangement provides a relatively larger 13 widthwise space in each panel 81 in which to inscribe the indices 82. If desired the indices may be inscribed on separate slips or labels each corresponding to a panel 81 and the indicator may be regarded as one 15 made up of separate labels.

The column stops having been adjusted to their proper positions along the column stop bar or rack 34 the operation of the machine will be as follows: The operator first 20 presses the column selecting key 61 and the corresponding column selecting stop 55 will be interposed in the path of the corresponding projection 54 on the column stop 35 with which the particular column selecting 25 stop co-acts. At the same time the carriage will be released and will move from right to left until arrested by the co-operation of the co-acting stops 54 and 55, thus at a single 30 operation bringing the carriage to the selected columnar field. The column stop which co-acts with the projected column selecting stop is arrested to the right of the series of denominational stops as will be understood from an inspection of Fig. 3. 35 The operator may then depress the desired denominational key which will interpose the associated denominational stop in the path of the projection or engaging portion 36 on the same column stop 35 by which an arrest 40 of the carriage was effected through its co-operation with the projected column selecting stop. The depression of the denominational key likewise effects, through its releasing means, a release of the carriage, thereby bringing the carriage to rest 45 at the proper denominational position within the selected columnar field.

Various changes may be made without departing from the spirit and scope of my invention.

What I claim as new and desire to secure by Letters Patent, is:—

1. In a typewriting machine, the combination of a carriage, a series of column stops carried by the carriage and each of said stops having a column selecting engaging portion that travels in one path and a denominational selecting engaging portion that travels in a distinct path, key controlled denominational selecting stops co-operative only with the denominational selecting engaging portion on each of the column stops, and key controlled column selecting stops each of which is co-operative only 55 with the column selecting engaging portion

on one of the column stops, the column selecting stops being so disposed that each of them is co-operative with its column stop before said stop reaches a position where any of the denominational selecting stops 70 is co-operative therewith.

2. In a typewriting machine, the combination of a carriage, a series of column stops carried by the carriage and each of said stops having a column selecting engaging portion that travels in one path and a denominational selecting engaging portion that travels in a distinct path, key controlled denominational selecting stops co-operative only with the denominational selecting engaging portion on each of the column stops; key controlled column selecting stops each of which is co-operative only with the column selecting engaging portion on one of the column stops, the column selecting stops being so disposed that each of them is co-operative with its column stop before said stop reaches a position where any of the denominational selecting stops is co-operative therewith, means controlled by an actuation of a column selecting stop for releasing the carriage, and means controlled by an actuation of a column selecting stop for releasing the carriage.

3. In a typewriting machine, the combination of a carriage, a series of relatively adjustable column stops carried by the carriage and each of said stops having a column selecting engaging portion that travels in one path and a denominational selecting engaging portion that travels in a distinct path, separate independently operated key controlled denominational selecting stops co-operative only with the denominational selecting engaging portion on each of the column stops; separate independently operated key controlled column selecting stops each of which is co-operative only with the column selecting engaging portion on one of the column stops, the column selecting stops being so disposed that each of them is co-operative with its column stop before said stop reaches a position where any of the denominational selecting stops is co-operative therewith, and automatically actuated carriage releasing means.

4. In a typewriting machine, the combination of a carriage, a series of column stops carried by the carriage and each of said stops having a column selecting engaging portion that travels in one path and a denominational selecting engaging portion that travels in a distinct path, denominational selecting stops co-operative only with the denominational selecting engaging portion on each of the column stops, column selecting stops each of which is co-operative only with the column selecting engaging portion on one of the column stops, the column selecting stops being so 120

disposed that each of them is co-operative with its column stop before said stop reaches a position where any of the denominational selecting stops is co-operative therewith.

5 therewith, a series of column selecting keys at the keyboard of the machine, each of said keys controlling one of said column selecting stops, and a series of denominational selecting keys at the keyboard of the machine,
10 each of said denominational keys controlling a denominational selecting stop.

5. In a typewriting machine, the combination of a carriage, a series of column stops carried by the carriage and each of said stops having a column selecting engaging portion that travels in one path and a denominational selecting engaging portion that travels in a distinct path, denominational selecting stops co-operative only with

29. column selecting stops co-operative only with the denominational selecting engaging portion on each of the column stops, column selecting stops each of which is co-operative only with the column selecting engaging portion on one of the column stops.

25 gagging portion on one of the column stops, the column selecting stops being so disposed that each of them is co-operative with its column stop before said stop reaches a position where any of the denominational selecting stops is co-operative therewith, a series of column selecting keys at the

30 series of column selecting keys at the keyboard of the machine, each of said keys controlling one of said column selecting stops, a series of denominational selecting keys at the keyboard of the machine, each of said denominational keys

35 denominational keys controlling a denominational selecting stop, means controlled by an actuation of any of said column selecting keys for releasing the carriage, and means controlled by an actuation of any of
40 said denominational selecting keys for releasing the carriage.

6. In a typewriting machine, the combination of a carriage; and tabulator mechanism comprising a pivoted V-shaped member which carries a stop at the apex thereof, a coöperative stop, and key controlled means for moving said V-shaped member into coöperative relation with said coöperative stop.

50 7. In a typewriting machine, the combination of a carriage; and tabulator mechanism comprising a series of nested V-shaped stop carrying pivoted members arranged at the rear of the machine, co-operative stops, 55 keys at the keyboard of the machine, and intermediate actuating connections between said keys and said V-shaped members.

8. In a typewriting machine, the combination of a carriage; and tabulator mechanism comprising a series of nested V-shaped members, stops carried by said members, said stops having different paths of movement but arranged with their contact faces in the same vertical fore and aft plane, keys for controlling said members, and a series of

column stops each having a contact portion which has a distinctive path of movement and is co-operative with but one of the stops on said V-shaped members.

9. In a typewriting machine, the combination of a carriage; and tabulator mechanism comprising a series of nested yoke-like individually movable members, column selecting stops carried by said members, said stops having different paths of movement but arranged with their contact faces in the same vertical fore and aft plane, column selecting keys for controlling said members, a series of relatively adjustable column stops each having a contact portion which has a distinctive path of movement and is co-operative with but one of said column selecting stops, and carriage releasing means operative on an actuation of any of said keys. 10
75
80

10. In a typewriting machine, the combination of a carriage; and tabulator mechanism comprising a series of yoke-like pivoted stop-carrying members, coöperative column stops, an abutment with which said yoke-like members are coöperative to limit their movements in one direction, a series of key controlled members, and a spring connecting each yoke-like member and its associated key controlled member to cause the two normally to move together. 90

11. In a typewriting machine, the combination of a carriage; and tabulator mechanism comprising a series of yoke-like pivoted stop-carrying members, the stop on each member having a distinctive path of movement, coöperative column stops each of which has a contact portion with a distinctive path of movement for coöperation with but one of the stops on the yoke-like members, an abutment with which said yoke-like members are coöperative to limit their movements in one direction, a series of key controlled members; and a spring connecting each yoke-like member and its associated key controlled member to cause the two normally to move together. 100 105 110

12. In a typewriting machine, the combination of a carriage; and tabulator mechanism comprising a series of yoke-like pivoted column selecting stop-carrying members carried by the frame of the machine, the stop on each member having a distinctive path of movement, coöperative column stops carried by the carriage and each of which has a contact portion with a distinctive path of movement for coöperation with but one of the column selecting stops, an abutment with which said yoke-like members are co-operative to limit their movements in one direction, a series of key controlled members, a spring connecting each yoke-like column selecting member and its associated key controlled member to cause the two normally to move together, and automatically operating carriage releasing means. 115 120 125 130

6

13. In a typewriting machine, the combination of a carriage; and tabulator mechanism comprising a series of pivoted nested yoke-like stop-carrying members, the stops on said members having distinctive paths of movement but the contact faces of said stops being in a single vertical fore and aft plane, coöperative relatively adjustable column stops, an abutment with which said yoke-like members are coöperative to limit their movements in one direction, a series of key controlled members, and a spring connecting each yoke-like member and its associated key controlled member to cause the two normally to move together.

14. In a typewriting machine, the combination of a carriage; and tabulator mechanism comprising a series of pivoted nested yoke-like stop-carrying column selecting members carried by the frame of the machine, the stops on said members having distinctive paths of movement but the contact faces of said stops being in a single vertical fore and aft plane, coöperative relatively adjustable column stops carried by the carriage and each having a contact portion that has a distinctive path of movement and is coöperative with but one of the column selecting stops, an abutment with which said yoke-like members are coöperative to limit their movements in one direction, a series of key controlled members, and a spring connecting each yoke-like member and its associated key controlled member to cause the two normally to move together.

15. In a typewriting machine, the combination of a carriage; and tabulator mechanism comprising a pivoted V-shaped member which carries a stop at the apex thereof, a coöperative stop, key controlled means for moving said V-shaped member into coöperative relation with said coöperative stop, and a series of key controlled denominational stops, each of which is coöperative with said coöperative stop.

16. In a typewriting machine, the combination of a carriage; and tabulator mechanism comprising a pivoted V-shaped member which carries a stop at the apex thereof, a coöperative stop, key controlled means for moving said V-shaped member into coöperative relation with said coöperative stop, and a series of key controlled denominational stops, each of which is coöperative with said coöperative stop, the relative arrangement between the stop on the V-shaped stop carrying member and the denominational stops being such that the stop on the V-shaped member is coöperative with the coöperative stop before any of the denominational stops co-act therewith.

17. In a typewriting machine, the combination of a carriage; and tabulator mechanism comprising a series of nested V-shaped stop carrying pivoted members arranged at

the rear of the machine, coöperative stops, keys at the keyboard of the machine, intermediate actuating connections between said keys and said V-shaped members, and a series of key controlled denominational stops each of which is coöperative with said coöperative stops. 70

18. In a typewriting machine, the combination of a carriage; and tabulator mechanism comprising a series of nested V-shaped stop-carrying pivoted members arranged at the rear of the machine, coöperative stops, keys at the keyboard of the machine, intermediate actuating connections between said keys and said V-shaped members, and a series of key controlled denominational stops each of which is coöperative with said coöperative stops, the relative arrangement of the first mentioned stops and said denominational stops being such that a coöperative 80 stop may co-act with one of the first mentioned stops before any of the denominational stops is coöperative with said coöperative stop.

19. In a typewriting machine, the combination of a carriage; and tabulator mechanism comprising a series of nested V-shaped stop-carrying pivoted members arranged at the rear of the machine, coöperative stops, keys at the keyboard of the machine, intermediate actuating connections between said keys and said V-shaped members, a series of key controlled denominational stops each of which is coöperative with said coöperative stops, means controlled by an actuation of any of said first mentioned stops for releasing the carriage, and means controlled by an actuation of any of said denominational stops for releasing the carriage. 90

20. In a typewriting machine, the combination of a carriage; and tabulator mechanism comprising a series of nested yoke-like individually movable members, column selecting stops carried by said members, said stops having different paths of movement but arranged with their contact faces in the same vertical fore and aft plane, column selecting keys for controlling said members, a series of relatively adjustable column stops each having a contact portion 110 which has a distinctive path of movement and is coöperative with but one of said column selecting stops, each of said column stops also having a second contact portion, and a series of key controlled denominational stops each of which is coöperative with the second contact portion on each of the column stops. 115

21. In a typewriting machine, the combination of a carriage; and tabulator mechanism comprising a series of nested yoke-like individually movable members, column selecting stops carried by said members, said stops having different paths of movement but arranged with their contact faces 125

in the same vertical fore and aft plane, column selecting keys for controlling said members, a series of relatively adjustable column stops each having a contact portion 5 which has a distinctive path of movement and is coöperative with but one of said column selecting stops, each of said column stops also having a second contact portion, a series of key controlled denominational 10 stops, each of which is coöperative with the second contact portion on each of the column stops, carriage releasing means controlled by an actuation of any of said column selecting stops, and carriage releasing means controlled by an actuation of any of said denominational stops.

22. In a typewriting machine, the combination of a carriage; and tabulator mechanism comprising a series of yoke-like pivoted stop-carrying members, coöperative column stops, an abutment with which said yoke-like members are coöperative to limit their movements in one direction, a series of key controlled members, a spring connecting 25 each yoke-like member and its associated key controlled member to cause the two normally to move together, and key controlled denominational stops each of which is coöperative with said coöperative 30 stops.

23. In a typewriting machine, the combination of a carriage; and tabulator mechanism comprising a series of yoke-like pivoted stop-carrying members, the stop on 35 each member having a distinctive path of movement, coöperative column stops each of which has a contact portion with a distinctive path of movement for coöperation with but one of the stops on the yoke-like members, each of said column stops also having a second contact portion, an abutment with 40 which said yoke-like members are coöperative to limit their movements in one direction, a series of key controlled members, a spring connecting each yoke-like member and its associated key controlled member to cause the two normally to move together, and a series of individually movable key 45 controlled denominational stops each of which is coöperative with the second contact portion on any of said column stops.

24. In a typewriting machine the combination of a carriage; and tabulator mechanism comprising a series of yoke-like pivoted column selecting stop-carrying members carried by the frame of the machine, the stop on each member having a distinctive path of movement, coöperative column stops carried by the carriage and each of which 55 has a contact portion with a distinctive path of movement for coöperation with but one of the column selecting stops, each of said column stops also having a second contact portion, an abutment with which said yoke-like members are coöperative to limit their 60

movements in one direction, a series of key controlled members, a spring connecting each yoke-like column selecting member and its associated key controlled member to cause the two normally to move together, a series 70 of individually movable key controlled denominational stops each of which is coöperative with the second contact portion on any of said column stops, carriage releasing means controlled by an actuation of any of 75 said column selecting stops, and carriage releasing means controlled by an actuation of any of said denominational stops.

25. In a typewriting machine, the combination of a carriage; and tabulator mechanism comprising a series of pivoted nested yoke-like stop-carrying members, the stops on said members having distinctive paths of movement but the contact faces of said stops being in a single vertical fore and aft 80 plane, coöperative relatively adjustable column stops, an abutment with which said yoke-like members are coöperative to limit their movements in one direction, a series of key controlled members, a spring connecting each yoke-like member and its associated key controlled member to cause the two normally to move together, and a series of 85 key controlled denominational selecting stops each coöperative with any of said 90 column stops.

26. In a typewriting machine, the combination of a carriage; and tabulator mechanism comprising a series of pivoted nested yoke-like stop-carrying column selecting 100 members carried by the frame of the machine, the stops on said members having distinctive paths of movement but the contact faces of said stops being in a single vertical fore and aft plane, coöperative relatively 105 adjustable column stops carried by the carriage and each having a contact portion that has a distinctive path of movement and is coöperative with but one of the column selecting stops, each of said column stops also 110 having a second contact portion, an abutment with which said yoke-like members are coöperative to limit their movements in one direction, a series of key controlled members, a spring connecting each yoke-like 115 member and its associated key controlled member to cause the two normally to move together, and a series of key controlled denominational selecting stops each coöperative with the second contact portion on any 120 of said column stops.

27. In a typewriting machine, the combination of a carriage; and tabulator mechanism comprising a pivot rod, a series of stop-carrying members pivoted on said pivot 125 rod, a series of key controlled levers which are likewise pivoted on said pivot rod, a spring connecting each stop-carrying member with its associated key controlled lever to cause the two normally to move together, 130

coöperative column stops, and means for arresting each of said stop carrying members before the associated key controlled lever reaches the limit of its movement.

5 28. In a typewriting machine, the combination of a carriage; and tabulator mechanism comprising a pivot rod, a series of stop-carrying members pivoted on said pivot rod, a series of key controlled levers which 10 are likewise pivoted on said pivot rod, a spring connecting each stop carrying member with its associated key controlled lever to cause the two normally to move together, a stop interposed in the paths of said stop-carrying members to limit the movement thereof in one direction, coöperative column stops, and carriage releasing means controlled by said key controlled levers.

29. In a typewriting machine, the combination of a carriage; and tabulator mechanism comprising a pivot rod, a series of nested yoke-like stop-carrying members pivoted on said pivot rod and each having an engaging portion that has a distinctive path 25 of movement, a series of key controlled levers which are likewise pivoted on said pivot rod, a spring connecting each stop-carrying member with its associated key controlled lever to cause the two normally to move together, and coöperative column stops each 30 of which has a contact portion that has a distinctive path of movement for coöperation with a given one only of the stops on said yoke-like members.

35 30. In a typewriting machine, the combination of a carriage; and tabulator mechanism comprising a pivoted tabulator stop-carrying member, a key controlled lever pivoted on the same pivotal center as the stop-carrying member and connected therewith by a butt joint, a spring connecting said lever and member and causing them to normally move together, a stop interposed in the path of the stop-carrying member, and 45 a coöperative tabulator stop.

31. In a typewriting machine, the combination of a carriage; and tabulator mechanism comprising a series of column stops each having on one side thereof a column 50 selecting engaging portion and having on another side thereof a denominational selecting engaging portion, key controlled denominational selecting means coöperating with the denominational selecting engaging portions on the column stops, column selecting means coöperative with column selecting engaging portions on the column stops, and separate and distinct keys for controlling said column selecting means.

60 32. In a typewriting machine, the combination of a carriage; and tabulator mechanism comprising a series of column stops

each having on one side thereof a column selecting engaging portion and having on another side thereof a denominational selecting 65 engaging portion, each column selecting engaging portion having a distinctive path of movement and all of the denominational selecting engaging portions moving in the same path, denominational selecting stops 70 each coöperative with any of the denominational selecting engaging portions on the column stops, and column selecting stops each having a distinctive path of movement and coöperative with a column selecting engaging 75 portion on but one of the column stops.

33. In a typewriting machine, the combination of a carriage; and tabulator mechanism comprising a series of column stops each having on one side thereof a column selecting engaging portion and having on another side thereof a denominational selecting 80 engaging portion, key controlled denominational selecting means coöperative with the denominational selecting engaging 85 portions on the column stops, column selecting means coöperative with column selecting engaging portions on the column stops, the column selecting means being arranged to the right of the denominational selecting 90 means, so that the column selecting means may co-act with a column stop before it reaches the denominational selecting means, and keys separate and distinct from the keys of the denominational selecting means for 95 controlling said column selecting means.

34. In a typewriting machine, the combination of a carriage; and tabulator mechanism comprising a series of column stops each having on one side thereof a column 100 selecting engaging portion and having on another side thereof a denominational selecting engaging portion, each column selecting engaging portion having a distinctive path of movement and all of the denominational 105 selecting engaging portions moving in the same path, denominational selecting stops each coöperative with any of the denominational selecting engaging portions on the column stops, and column selecting stops each having a distinctive path of movement and coöperative with a column selecting 110 engaging portion on but one of the column stops, the column selecting stops being arranged to the right of the denominational stops so that a column selecting stop may 115 co-act with a column stop before that latter reaches any of the denominational stops.

Signed at Leeds, England, this 18th day of December, 1912.

ROBERT BERRIER KETTLEWELL.
